UNITED STATES PATENT OFFICE

161,888

PARKING LOT METER

Lewis G. Wilkin, Cincinnati, Ohio

Application August 31, 1950, Serial No. 11,998

Term of patent 14 years

(Cl. D52—3)

To all whom it may concern:

Be it known that I, Lewis G. Wilkin, residing at Cincinnati, Hamilton County, State of Ohio, have invented a new, original, and ornamental Design for a Parking Lot Meter, of which the following is a specification, reference being had to the accompanying drawing, forming part thereof.

In the drawing,

Figure 1 is a front view in perspective of a parking lot meter, showing my new design.

Figure 2 is a rear view in perspective thereof.

I claim:

The ornamental design for a parking lot meter, as shown.

LEWIS G. WILKIN.
